CLAIM

The ornamental design for a baseball pitching practice platform, as shown and described.

DESCRIPTION

FIG. 1 is a top perspective view of a baseball pitching practice platform showing my new design;

FIG. 2 is a top plan view thereof;

FIG. 3 is a front elevational view thereof;

FIG. 4 is a right side elevational view thereof; the side opposite being a mirror image, and

FIG. 5 is a rear elevational view thereof.
